UNITED STATES PATENT OFFICE.

OTTO C. OEHLER AND WILLIAM HILLEBRAND, OF ST. LOUIS, MISSOURI.

MACHINE AND METHOD FOR MAKING DRY-PRESSED ROUGH-TEXTURE BRICK.

Application filed December 11, 1922. Serial No. 606,080.

To all whom it may concern:

Be it known that we, OTTO C. OEHLER and WILLIAM HILLEBRAND, citizens of the United States, residing in the city of St. Louis, State 5 of Missouri, have invented a certain new and useful Improvement in Machines and Methods for making Dry-Pressed Rough-Texture Brick, of which the following is a full, clear, and exact description, such as will enable 10 others skilled in the art to which it appertains to make and use the same.

This invention relates to the manufacture of dry-pressed, rough texture brick.

One object of our invention is to provide 15 a dry-pressed, rough texture brick that is very rough, irregular and uneven, and consequently, more attractive than the dry-pressed, rough texture brick now on the market.

Another object is to provide a novel method of producing such a brick.

And still another object is to provide an apparatus of simple design and inexpensive construction for converting a smooth face, 25 dry-pressed brick into a brick that has a rough, jagged and uneven exposed surface. Other objects and desirable features of our invention will be hereinafter pointed out.

Figure 1 of the drawings is a side elevational view of an apparatus constructed in accordance with our invention for converting a smooth face, dry-pressed brick into a rough texture brick.

Figure 2 is a perspective view of a stand- 35 ard rough texture brick produced by said apparatus.

Figure 3 is a perspective view of a rough texture brick whose ends and one side face are serrated.

Figure 4 is a side elevational view of the 40 scoring mechanism; and

Figure 5 is a transverse sectional view, taken on the line 5—5 of Figure 1, looking in the direction indicated by the arrows.

The method that is now used to make dry-pressed, rough texture brick consists of 45 forming the brick in a mold box provided with fluted or corrugated surfaces that produce ribs or corrugations on certain faces 50 of the brick, removing the brick from the mold box and thereafter passing the brick through an apparatus that forms scratches or serrations in the corrugations of the brick at right angles to the ribs on said faces. As 55 the rough surfaces of the brick are formed principally by molded ribs or corrugations

that are straight, regular and even, the brick lacks the jagged and uneven appearance that is sought after in bricks of the so-called "matt" or texture surface type. Accordingly, the present method of making dry-pressed, rough texture brick is deficient, in that it does not produce a brick that is sufficiently rough and uneven to be considered artistic. Another objectionable feature of 60 said method is that it necessitates the use of a special mold box which has to be installed in the press each time the press is used for making rough texture brick. The labor cost of substituting one mold box for 65 another is considerable, and as it takes about two days to remove one mold box and install another, the press is out of commission or service four days every time rough texture brick are made in the press, two days 70 being required to substitute the corrugated mold box for the smooth face mold box to put the press in condition to be used for manufacturing rough texture brick and two days being required to restore the press to 75 its former condition. With a small brick manufacturer this is a serious thing, for it practically prohibits the manufacture of dry-pressed, rough texture brick in small 80 quantities, as it is not feasible, from a commercial standpoint, to shut the press down for a total of four days every time it is used 85 for making rough texture brick.

Our invention overcomes the necessity of using a corrugated mold box or mold box of 90 other special design in the manufacture of dry-pressed, rough texture brick; it overcomes the necessity of shutting the press down for several days and installing a different mold box every time the press is used 95 for making rough texture brick and it produces an artistic brick that has the rough, uneven and jagged appearance sought for in bricks of the "matt" or texture surface type.

Briefly stated, our method consists in 100 forming a dry-pressed brick in a conventional mold box provided with smooth surfaces, removing the brick from said mold box at the completion of the pressing operation, and thereafter passing the molded 105 brick through an apparatus that converts the smooth surface on one or more faces of the brick into a rough, uneven and jagged surface that is made up of a number of scratches, serrations or score marks that extend in the same general direction over the 110 surface, but which are more or less broken

up by portions of the surface of the brick that crumble during the scoring operation.

Any suitable press and smooth face mold box may be used to form the brick and various kinds of apparatus may be used to scratch, score or serrate the faces of the brick which it is desired shall have a rough texture surface. We prefer, however, to feed the molded brick either manually or 10 automatically by suitable mechanical means to a scoring apparatus of the kind illustrated in the drawings which is provided with means for simultaneously scoring, or serrating three faces of the brick. The apparatus is constructed in such a way that the scoring devices can be adjusted to vary the depth of the serrations formed in the faces of the brick, and it is also preferably constructed in such a manner that it can be 20 used to produce a standard rough texture brick of the kind shown in Figure 2 having its ends and one of its edges serrated, or a brick of the kind shown in Figure 3 having its ends and one of its flat faces serrated.

Referring to the drawings, A designates the bed plate of the machine. B designates a horizontally-disposed feed table on which a plurality of molded bricks w are adapted to be arranged, one behind the other, as shown in Figure 1, C designates as an entirety a scoring mechanism and D designates a reciprocating plunger for feeding the brick longitudinally of the table B; so as to cause them to be acted upon by the scoring mechanism C. In the machine herein illustrated the scoring mechanism is composed of two side frames or supporting elements 1 connected to the bed plate of the machine, two horizontally-disposed shafts 2 and 2^a mounted in the side frames 1 and provided with scoring devices 3 and 3^a, respectively, and two sets or pairs of vertically-disposed shafts 4 and 4^a mounted in the side frames 1 and provided with horizontally-disposed scoring devices 5 and 5^a, respectively, that project laterally from said shafts. The shafts 2 and 2^a are arranged in the same horizontal plane, one behind the other, and the scoring devices 3 and 3^a on said shafts project downwardly from same at an angle of approximately 45° so as to form serrations, scratches or score marks w in the top faces of the molded brick that are moved longitudinally of the table B by the feeding device D. Preferably the scoring devices 3 on the shaft 2 are arranged in staggered relation with the scoring devices 3^a on the shaft 2^a so as to form serrations in the brick that are spaced close enough together to tend to cause the material in the face of the brick to crumble, and thus produce a jagged and uneven surface that is sufficiently rough and uneven to impart an artistic appearance to the brick. The vertical shafts 4 and 4^a in each of the side frames 1 are arranged in the same ver-

tical plane, one behind the other, and the scoring devices 5 and 5^a on said shafts are also preferably arranged in staggered relation. Any suitable kind of scoring devices may be used and said devices may be mounted in any suitable way in the shafts that support same. We prefer, however, to connect the scoring devices to their supporting shafts by set screws 6, as shown in Figure 5, so as to enable said scoring device to be adjusted to compensate for wear.

If the brick are arranged edgewise on the table B in advance of the plunger D, the forward stroke of said plunger causes the brick to be fed forwardly past the scoring devices 3, 3^a, 5 and 5^a, thereby producing serrations w in the top faces of the brick and serrations w' in the end faces of the brick, as shown in Figure 2. In order that the machine may be used to form brick of the kind shown in Figure 3 the bed plate A of the machine is provided with notches or depressions 7 in which the side frames 1 of the scoring mechanism can be set, as indicated in broken lines in Figure 1, so as to arrange the horizontal shafts 2 and 2^a closer to the feed table B of the machine, thus causing the ends and the top faces of the brick to be scored in the manner shown in Figure 3 when the brick are arranged flatwise on the table B and fed through the scoring mechanism by the plunger or feeding devices D.

The shafts that carry the serrating devices are maintained in a stationary position during the scoring operation and in order that the depth of the scratches or serrations formed in the brick may be varied, we have provided the machine with means for adjusting the horizontal shafts 2 and 2^a so as to vary the angle of the downwardly-projecting scoring devices 3 and 3^a on said shafts, and means for adjusting the shafts 4 and 4^a so as to vary the angle of the laterally-projecting scoring devices 5 and 5^a on said shafts. Various means may be used for adjusting said shafts, but we prefer to equip the scoring mechanism with a manually operated adjusting shaft 8 that is equipped with worms 9 which mesh with worm gears 10 on the shafts 2 and 2^a and equip each of the side frames 1 with a manually operated adjusting shaft 11 that is provided with worms 12 which mesh with worm gears 13 on the upper ends of the vertical shafts 4 and 4^a, as shown more clearly in Figures 4 and 5. By manipulating the shaft 8 the horizontal shafts 2 and 2^a can be turned so as to change the angle of the scoring devices on said shafts, and thus vary the depth of the cuts or serrations made in the top faces of the brick by said scoring devices. Similarly the shafts 11 can be manipulated so as to vary the angle of the horizontally-disposed scoring devices 5 and 5^a, and thus

vary the depth of the cuts or serrations made in the end faces of the brick by said scoring devices.

Any suitable means can be used for operating the feeding device D which moves the molded brick into position to be acted upon by the scoring mechanism, and as previously stated, the molded brick can be placed on the feed table B by hand or can be fed automatically onto said table by a mechanical feeding means. In the machine herein illustrated the plunger D is reciprocated longitudinally of the feed table B by a link 14 connected to the plunger D and to a crank 14^a on a shaft 15 that is provided with a gear 16 which meshes with a pinion 17 on a drive shaft 18 provided with a belt pulley 19.

The above described method of making dry-pressed, rough texture brick not only produces brick that have a more attractive appearance than the dry-pressed, rough texture brick now on the market, but it also overcomes the necessity of changing the mold box of the brick press every time the press is to be used for making rough texture brick. Accordingly, it effects a considerable saving in the cost of manufacturing rough texture dry-pressed brick and makes it practicable for a small brick manufacturer to use the same press for making smooth face brick and rough texture brick, because the mold box of the press does not have to be changed each time it is used to make rough texture brick. It is, of course, immaterial, so far as our method is concerned, what particular type or kind of apparatus is used for serrating or scoring the molded brick after they have been removed from the mold box of the press, but when a scoring or serrating machine of the kind herein illustrated is used, the character of the rough surfaces produced on the brick can be modified easily by changing the adjustment of the scoring devices, and standard dry-pressed brick or brick that are adapted to be arranged in a wall edgewise can be produced in the same scoring machine simply by changing the position of the scoring mechanism on the bed plate of the machine.

Having thus described our invention, what we claim and desire to secure by Letters Patent is:

1. A method of making a dry-pressed, rough texture brick, characterized by forming a dry-pressed brick in a smooth face mold box, removing the brick from said mold box at the completion of the pressing operation, and thereafter ornamenting the brick by moving it relatively to devices that impart a jagged, rough and uneven appearance to one or more faces of the brick by forming scratches or serrations in said faces.

2. A machine for imparting a rough texture surface to a dry-pressed brick, provided

with a scoring mechanism comprising a horizontally-disposed shaft and a vertical shaft arranged adjacent the path of travel of a brick that is to be scored and adapted to be maintained in a stationary position during the scoring operation, angularly-disposed scoring devices on said shafts, and means for adjusting said shafts to change the angle of said scoring devices.

3. A machine for imparting a rough texture surface to a dry-pressed brick, comprising a feed table over which a molded brick is adapted to be moved, a horizontally-disposed shaft arranged above said table and provided with a gang of downwardly-projecting scoring devices that form serrations in the top surface of a brick positioned on said table, said shaft being maintained in a stationary position during the scoring operation, and means for turning said shaft to simultaneously adjust all of said scoring devices when it is desired to vary the depth of the serrations formed in the brick.

4. A machine for imparting a rough texture surface to a dry-pressed brick, comprising a feed table over which a molded brick is adapted to be moved, a horizontally-disposed shaft arranged above said table and provided with downwardly-projecting scoring devices that form serrations in the top surface of a brick positioned on said table, means for turning said shaft to vary the depth of the serrations formed in the brick, vertically-disposed shafts arranged at opposite sides of said table and provided with scoring devices for forming serrations in the ends of the brick, said horizontal and vertical shafts being maintained in a stationary position during the scoring operation, and means for adjusting said vertical shafts to vary the depth of the serrations formed by the scoring devices on said shafts.

5. A machine for imparting a rough texture surface to dry-pressed brick, comprising a table, means for feeding molded brick over said table, a scoring mechanism comprising side frames arranged adjacent said table, a plurality of horizontally-disposed shafts carried by said side frames and provided with depending scoring devices arranged in staggered relation, and vertical shafts carried by said side frames and provided with laterally-projecting scoring devices arranged in staggered relation, said shafts being maintained in a stationary position during the scoring operation.

6. A machine for imparting a rough texture surface to dry-pressed brick, comprising a table, means for feeding molded brick over said table, a scoring mechanism comprising side frames arranged adjacent said table, a plurality of horizontally-disposed shafts carried by said side frames and provided with depending scoring devices arranged in staggered relation, vertical shafts

carried by said side frames and provided with laterally-projecting scoring devices arranged in staggered relation, said shafts being maintained in a stationary position during the scoring operation, means for adjusting said horizontal shafts to vary the depth of the serrations formed by the scoring devices thereon, and means for adjusting said vertical shafts to vary the depth of the serrations formed by the scoring devices on said vertical shafts.

7. A machine for imparting a rough texture surface to dry-pressed brick, comprising a bed plate, a table, means for feeding molded brick over said table, a scoring mech-

anism comprising side frames mounted on said bed plate, said bed plate having depressions in which said side frames can be positioned when the brick being operated on are arranged flatwise on the table, shafts carried by said side frames and provided with scoring devices arranged so that they will form serrations in the ends and in the top side of the brick moved over said table, and means for turning said shafts to adjust the scoring devices thereon, said shafts being maintained in a stationary position during the scoring operation.

OTTO C. OEHLER.

WILLIAM HILLEBRAND.
